SEWING MACHINE CABINET OR SIMILAR ARTICLE

Joseph A. Crozier, Trumann, Ark., Walter F. Nessen,
Jeffersontown, Ky., and Elbert J. Stanley, Goztepe-
Kadikoy, Istanbul, Turkey, assignors to The Singer
Company, Elizabeth, N.J., a corporation of New
Jersey

Filed May 7, 1964, Ser. No. 79,879

Term of patent 14 years

(Cl. D33—12)

Fig. 1

Fig. 2

Fig. 3

FIG. 1 is a front perspective view of a sewing machine cabinet showing our new design,

FIG. 2 is a view similar to FIG. 1 with the front of the cabinet opened to form a table and with one of the trio of panels removed to be replaced by the bed of a sewing machine, and

FIG. 3 is a partial right end perspective view of the cabinet.

The unshown outer surface of the rear wall is plain.

We claim:

The ornamental design for a sewing machine cabinet or similar article, substantially as shown and described.
